UNITED STATES PATENT OFFICE

165,070

TOY AIRPLANE

Robert L. Hayman, Chicago, Ill.

Application April 19, 1951, Serial No. 14,891

Term of patent 3½ years

(Cl. D34—15)

To all whom it may concern:

Be it known that I, Robert L. Hayman, a citizen of the United States, residing at Chicago, in the county of Cook and State of Illinois, have invented a new, original, and ornamental Design for Toy Airplane, of which the following is a specification, reference being had to the accompanying drawing, forming a part thereof.

Fig. 1 is a top plan view of a toy airplane, showing my new design;

Fig. 2 is a side elevational view thereof;

Fig. 3 is a front elevational view thereof; and

Fig. 4 is a rear elevational view thereof.

I claim:

The ornamental design for a toy airplane, as shown.

ROBERT L. HAYMAN.
